Primary Examiner — Eric Goodman*Assistant Examiner* — Daniel J Domino(74) *Attorney, Agent, or Firm* — McGinn IP Law Group, PLLC(57) **CLAIM**

The ornamental design for a hose clamp, as shown and described.

DESCRIPTION

FIG. 1 is a rear perspective view of a hose clamp showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view of alternate usage thereof;

FIG. 9 is an enlarged front perspective view thereof;

FIG. 10 is a cross-sectional view taken along 10-10 of FIG. 9; and,

FIG. 11 is an enlarged rear perspective view thereof.

The broken lines shown are included for the purpose of illustrating the unclaimed portions of a hose clamp and form no part of the claimed design. The dash-dot line represents boundaries between the claimed portion and unclaimed portion.
